UNITED STATES PATENT OFFICE.

CHARLES DAVID BONSALL AND FRANK W. WOLFF, OF PARNASSUS, PENNSYLVANIA,
ASSIGNORS TO P. H. MURPHY COMPANY, OF PARNASSUS, PENNSYLVANIA, A COR-
PORATION OF PENNSYLVANIA.

METAL CARLINE.

1,315,756.

Specification of Letters Patent. Patented Sept. 9, 1919.

Application filed January 20, 1919. Serial No. 271,973.

To all whom it may concern:

Be it known that we, CHARLES DAVID BON-
SALL and FRANK W. WOLFF, citizens of the
United States, and residents of the city of
5 Parnassus, in the county of Westmoreland
and State of Pennsylvania, have invented a
new and useful Improvement in Metal Car-
lines, of which the following is a specifica-
tion.

10 This invention relates to metal carlines
for car roofs and particularly to the form
of carline and the means for securing the
ends of said carline to the side plates of
the car. The carline brackets shown in the
15 accompanying drawing are claimed in our
separate application Serial No. 300,822, filed
May 31, 1919.

One of the principal objects of the pres-
ent invention is to produce a strong and
20 light-weight carline adapted to be used in
connection with cars having either metal
or wooden side plates and which can be
pressed from a rectangular sheet of metal
without being trimmed. Another object is
25 to secure a distribution of the metal through-
out the carline suitable for resisting the
tendency of the carline to rotate or twist
due to the end thrust of the purlins or to
the racking and weaving of the car. An-
30 other object is to improve the bracket end
members and provide for securing them to
the body member of the carline.

The invention consists principally in a
carline pressed from a single piece of metal
35 of uniform width, the carline being of sub-
stantially Z-shaped section at its middle
with its web portion gradually diminish-
ing in height from the middle toward each
end, the surplus metal gained thereby be-
40ing formed into a vertical flange whose
depth increases from the middle toward the
ends and which extends downwardly from
the top horizontal flange of the Z to the
plane of the lower flange of the Z where it
45 is then bent outwardly near the end portion
of the carline, thus forming an inverted U
shape near each end. The invention also
consists in improved bracket members which
form means for securing the ends of the car-
50 line to the side plates. The invention fur-
ther consists in the arrangements and com-

bination of parts hereinafter more clearly
described and claimed.

In the accompanying drawing, wherein
like numerals refer to like parts in the sev- 55
eral views,

Figure 1 is a plan view of a carline and
end bracket members embodying our inven-
tion shown in connection with the side plates
of a car roof;

Fig. 2 is a side elevation of the carline
and end bracket members shown in Fig. 1,
the side plate being shown in cross-section;

Figs. 3, 4, 5, and 6 are vertical cross-sec-
tion views taken through the carline on the 65
lines 3-3, 4-4, 5-5, and 6-6, respectively;

Fig. 7 is a side elevation of the side plate
and bracket member showing the carline in
end elevation;

Fig. 8 is a fragmentary plan view of the 70
carline and end bracket adjacent to the side
plate showing a modification of the struc-
ture;

Fig. 9 is a side elevation of the carline and
bracket member shown in Fig. 8, the side 75
plate being shown in cross-section;

Fig. 10 is a side elevation of the side plate
and bracket member shown in Figs. 8 and 9,
the carline being shown in end elevation;

Fig. 11 is a fragmentary plan view simi- 80
lar to Fig. 8 showing a further modification
of the invention;

Fig. 12 is a side elevation of the carline
and bracket member shown in Fig. 11, the 85
side plate being shown in cross-section;

Fig. 13 is a vertical cross-section taken
through the car line on the line 13-13 in
Fig. 11 looking toward the inner face of 90
the side plate.

In the construction shown in Figs. 1 to 7 90
of the drawings, the carline which is pressed
from a piece of metal of uniform width,
extends from side to side of the car and
comprises a vertical web portion 14 having
a lateral flange 15 on its lower edge dis- 95
posed on one side of the web and a lateral
flange 16 on its upper edge disposed on the
opposite side of the web. The oppositely
projecting flanges 15 and 16 are of the same
width and extend continuously from end to 100
end of the carline.

The web 14 of the carline gradually di-

minishes in height from its middle toward each end, thus affording surplus metal, which is utilized in forming a vertical flange 17, which projects downwardly from the lateral flange 16 at the upper edge of the carline. As the height of the web portion 14 of the carline diminishes in depth toward each end, there is a corresponding increase in depth of the downwardly projecting flange 17 from the middle of the carline toward each end. At the point where the vertical flange 17 thus formed reaches the plane of the bottom flange 15 on the opposite side of the web portion 14 of the carline whence the marginal portion of said flange 17 is bent outwardly forming a horizontal flange 18. The horizontal flange 18 increases in width toward the end of the carline, where it terminates in a flange of the same width as the flange 15 on the opposite side of the carline. The bending down of the marginal portion of the upper horizontal flange 15 on each side of the center of the carline into the vertical flange 17 and the bending horizontally of the end portion of the margin of the vertical flange 17 thus formed into the lower horizontal flange 18, which lies in the horizontal plane of the bottom lateral flange 15 on the opposite side of the web 14, results in a carline which gradually changes from a substantially Z-shaped section at its middle into a channel section at each end having lateral base flanges 15 and 18.

Each end of the carline is secured to the adjacent wooden side plate 19 by means of a channel-shaped bracket 20 which straddles the top of the side plate and is secured thereto by means of horizontal bolts 21 which pass through both flanges 22 of the channel-shaped bracket and side plate 19.

The end of the carline projects over the side plate and rests on the channel-shaped bracket 20, which is slit crosswise on each side of its middle from the bottom of the inner flanges to the top of the outer flange, and the metal located between the slits is bent up forming a tongue 23 which projects into the channel-shaped end of the body member of the carline and is securely riveted to the under side of the flange 16 of said body member. The lateral flanges 15 and 18 located on each side of the carline are also securely riveted to the horizontal web portion of the channel-shaped bracket member 20.

In the construction shown in Figs. 8 to 10 an angle bracket is shown with its horizontal flange 24 resting on the side plate of the car and projecting inwardly past the inner face of the side plate and with its vertical flange 25 projecting downwardly outside of the side plate. Then ends of the lateral flanges 15 and 18 of the carline are bent down as at 26 and the bracket member

and carline are secured to the side plates by means of horizontal bolts 27 which extend through the vertical flange 25 of the angle bracket and the side plate. The horizontal flange of the angle bracket member is slit back from its inner margin on opposite sides of the center thereby forming a tongue 28 which is riveted to the under side of the flange 16 in a manner similar to tongue 23 of the channel-shaped bracket 20 shown in Figs. 1, 2, and 3.

In the construction shown in Figs. 11 to 13, the bracket member 29 is channel-shaped and straddles the top of the side plate. The outer flange of the bracket is secured to the side plate by means of bolts 30 which extend horizontally through the side plate. The top web portion of the bracket member is secured in position by means of bolts 31 which extend vertically through the side plates. The inner vertical flange of the bracket is bent inwardly horizontally, as at 32, and forms a support for the end of the carline which rests thereon and has its flanges 15 and 18 riveted securely thereto. The inner flange of the bracket is slit crosswise of the bracket on each side of the center, and the metal between the slits is bent upwardly in the form of a tongue 33 which is riveted to the top of the flange 16 of the carline thereby constituting additional securing means for the ends of the carline.

From the foregoing description, it is evident that the carline can be riveted or bolted directly to the tops of the side plates without the use of separate bracket or end members, especially when the carline is used in connection with metal side plates. By reason of the top flange 16 of the carline being stiffened by the vertical flange 17 thereof, the carline is stiffer and stronger than ordinary Z-shaped carlines of the same weight. The vertical flange 17, together with the web portion 14 of the carline form vertical webs on each side of the top flange 16 of the carline, thus forming a strong section adapted to resist compression stresses which have a tendency to cause buckling. This stiffening of the top flange 16 of the carline by means of the additional flange 17 also resists twisting or rotating due to the end thrust from the purlins and ridge pole.

The widening out of the ends of the carline acts after the manner of a gusset and affords wide bearing ends for attaching the end of the body portion of the carline to the bracket members, which in turn are securely bolted or otherwise secured to the side plates, while the slitting of the bracket members permits these members to engage the ends of said body portion and to be secured thereto across their entire end portion.

It is evident that the bracket members may also be used for securing carlines of various commercial shapes to the side plates.

and that changes in the above described construction may be made without departing from the invention. Therefore, we do not wish to be limited to the exact form of carline and end brackets shown.

What we claim is:

1. A carline pressed from a metal plate of uniform width comprising a middle portion of Z-section, whose vertical web diminishes in depth from the middle toward each end, the surplus metal being turned down over the outer margin of the top flange to form channel-shaped ends.
2. A carline pressed from a metal plate of uniform width comprising a middle portion of Z-shaped section whose web diminishes in depth from the middle toward each end, the surplus metal obtained thereby being turned down over the outer margin of the upper flange and thence outwardly in the plane of the lower flange to form channel-shaped ends.
3. A carline comprising a middle portion of Z-section whose web portion diminishes in height from the middle toward each end, the section of said carline gradually changing from a Z-section at its middle into a channel section at each end.
4. A carline comprising a vertical web portion whose depth diminishes from the middle of said carline toward each end, said web portion having lateral flanges at its upper and lower edges disposed on opposite sides thereof, the upper lateral flange of said carline having a vertical flange projecting downwardly from its outer margin whose depth increases from the middle toward each end of said carline.
5. A carline comprising a vertical web portion whose depth diminishes from the middle toward each end of said carline said web portion having a lateral flange at its upper edge disposed on one side of the web and a lateral flange at its lower edge disposed on the opposite side of the web, both of said flanges being continuous and of the same width throughout, said carline having a vertical flange depending from said upper lateral flange thereof, the depth of said vertical flange increasing from the middle toward each end to the plane of the lower lateral flange of said carline where it terminates in the form of a horizontal flange.
6. A carline comprising a vertical web portion whose depth diminishes from the middle toward each end, said web portion having a lateral flange at its upper edge disposed on one side of the web and a lateral flange at its lower edge disposed on the opposite side of the web, both of said lateral flanges being continuous and of the same width throughout, said carline having a vertical flange depending from said upper lateral flange thereof, whose lower edge inclines downwardly on each side of the middle of said carline toward the plane of the lower lateral flange of said carline where it terminates in an outwardly projecting horizontal flange whose width increases toward the ends of the carline.
7. A carline comprising a middle portion of Z-shaped section whose depth diminishes toward each end and gradually changes into end portions of channel section having lateral flanges, said lateral flanges being turned down at the ends of the carline.
8. A carline having end portions of channel-shaped section and brackets for securing the ends of the carline in place, said brackets comprising a body portion adapted to be secured to the side plate and a tongue portion adapted to be secured to the ends of the carline.
9. A carline comprising a middle portion of Z-shaped section and end portions of channel-shaped section, and brackets for securing the ends of said carline to the side plates of the car, said brackets comprising a body portion adapted to be secured to the side plate and a tongue portion adapted to be secured to the channel-shaped end portions of the carline.
10. A carline comprising a middle portion of Z-shaped section gradually changing into end portions of channel-shaped section having lateral base flanges, and brackets for securing the ends of said carline to the side plates, said brackets comprising a body portion adapted to straddle and be secured to the side plate and an inwardly projecting tongue portion secured to the web portion of the channel-shaped end portion of said carline.
11. A carline comprising a middle portion of Z-shaped section whose depth diminishes toward each end and gradually changes into end portions of channel-section having lateral flanges, and brackets for securing the ends of the carline to the side plates of the car, said brackets having a channel-shaped body portion adapted to straddle and be secured to the side plate, said bracket members being slit crosswise across the top on each side of the center to form a tongue which is secured to the web portion of the channel-shaped end of said carline, the lateral base flanges of the channel-shaped ends of said carline resting on and being secured to the body portion of said brackets.
12. A carline comprising a middle portion of Z-shaped section whose height diminishes toward each end and gradually changes into end portions of channel-section having lateral base flanges, and brackets for securing the ends of the carline to the side plates of the car, said brackets having a body portion of channel-section adapted to straddle and be secured to the side plate, the inner flange of said bracket member being bent

inwardly and secured to the ends of said carline, said bracket member being slit cross-wise on each side of the center and the metal between the slits being struck up to form a tongue, said tongue being secured to the web portion of the channel-shaped ends of said carline.

13. A carline comprising a vertical web portion of diminishing depth from its middle toward each end, said web portion having oppositely projecting top and base flanges, the top flange having a vertical flange projecting downwardly from its outer margin, and increasing in depth from the middle of the carline toward each end to the plane of the base flange of said carline where it extends outwardly in the form of a horizontal flange thereby forming a channel-section at the ends of said carline having lateral

base flanges, said base flanges being turned 20 down between the side plates, and angle brackets resting on the side plates with their vertical flange projecting downwardly on the outside of the side plate, means for securing the vertical flange of said angle bracket and the downturned lateral base flanges of the channel-shaped ends of the carline to the opposite sides of the side plate, the horizontal flanges of said angle bracket being secured to the base flanges of the channel-shaped ends of the carline and having a tongue struck up therefrom which is secured to the web portion of the channel-shaped ends of the carline.

Signed at Parnassus, Pa., this 13th day of 35 January, 1919.

CHARLES DAVID BONSALL.
FRANK W. WOLFF.
